**VACUUM CAPPING MACHINE AND
COMPONENTS THEREOF**

Robert K. McEiroy, Elmhurst, and Frank P. Lawler, Chicago, Ill., assignors to Continental Can Company, Inc., New York, N.Y., a corporation of New York
Filed July 7, 1961, Ser. No. 122,498
30 Claims. (Cl. 53—96)

The invention relates to a new and improved container sealing machine including as a part thereof new and improved components. More specifically, the invention is directed to a container evacuation and cap application machine capable of high speed efficient operation in a fully automatic manner, the machine including certain components which also constitute parts of the present invention.

There are many different proposed types of vacuum capping machines, some of which are capable of efficient use. Such machines are quite complicated with regard to structural and operational aspects and are difficult to maintain in efficient operating condition. Furthermore, vacuum sealing machines as known prior to this invention are often limited in use depending on the particular product with which the containers are filled. By way of example, powdery particulate materials, such as instant coffee and the like, create vacuum packaging difficulties due to their tendency to be readily displaced from the container when the container is subjected to vacuumization conditions. Filtering means such as a cloth or screen have been proposed for positioning over the open top of a container during evacuation thereof. However, a low residual oxygen condition must exist in the container headspace and in the interstices between particles of the contents at the time the cap or closure is applied to the container and the attempts to meet this requirement have led to very complicated, often unworkable, mechanical arrangements. In this regard, the fine and powdery material can be drawn against the cap and interfere with the forming of an effective hermetic seal.

With regard to the mechanical complexities of known forms of vacuum capping machines, it will be appreciated that there are many operational steps involved which are difficult to mechanically regulate effectively under high speed operational conditions. For high speed operation, it is essential that the various steps involving evacuation, cap delivery, and cap application be carried out efficiently and consistently. In order to obtain and maintain consistently controlled operation of a high speed capping machine, there has been a tendency to design highly complicated machines and components which are difficult and expensive to maintain.

It is an object of the present invention to provide a new and improved vacuum capping machine and new and improved components thereof which are particularly adapted for efficient and consistent high speed operation accompanied by simplified maintenance.

Another object is to provide a new and improved machine for automatically evacuating air from the head space of a filled container and capping the same, the machine incorporating therein a plurality of uniquely arranged mechanically operating assemblies which provide for improved savings and ease in maintenance thereof.

Still another object is to provide a new and improved vacuum capping machine and components thereof, the machine being adapted for high speed operation for efficient evacuation of air from the head space of containers filled with powdery or particulate material, and also from the interstices between particles of the fill, certain new and improved components of the machine being specially designed to provide for retention of the particulate

2

material in the container during the evacuation cycle thereof and during cap application thereto.

Additional objects involve the provision of new and improved components for use in a vacuum capping machine, such components including a unique drive arrangement between upper and lower rotating assemblies, a new and improved capping chamber unit, a new and improved cap delivery device, a new and improved container gripping arrangement, and a new and improved container positive feed arrangement.

Other objects not specifically set forth will become apparent from the following detailed description of the invention made in conjunction with the accompanying drawings wherein:

15 FIG. 1 is a partial vertical section of the vacuum capping machine of the invention with certain parts thereof illustrated in elevation, this view being taken generally along line 1—1 of FIG. 2;

20 FIG. 2 is a top plan of the machine as viewed generally along line 2—2 in FIG. 1;

FIG. 3 is a sectional plan view of the machine taken generally along line 3—3 in FIG. 1 and illustrating different operational aspects of the machine as compared with those shown in FIG. 2;

25 FIG. 4 is a sectional plan view taken generally along line 4—4 in FIG. 1, this view being intended primarily to illustrate certain aspects of the drive arrangement of the machine;

FIG. 5 is a sectional view of the cap loading mechanism of the machine taken generally along line 5—5 in FIG. 1;

FIG. 6 is a partial vertical section of one container evacuation and capping assembly;

FIG. 7 is a top plan view of the assembly of FIG. 6;

35 FIG. 8 is a transverse section of a portion of the assembly of FIG. 6 taken generally along line 8—8 therein;

FIG. 9 is a transverse section of another portion of the assembly of FIG. 6 taken generally along line 9—9 therein;

40 FIG. 10 is still another transverse section of a portion of the assembly of FIG. 6 taken generally along line 10—10 therein;

FIG. 11 is an enlarged vertical section of the filter and cap application head of the assembly of FIG. 6;

45 FIG. 12 is a partly sectioned elevation of the filter and cap application head of FIG. 11 illustrating certain parts thereof in different operative positions;

FIG. 13 is a bottom plan view taken generally along line 13—13 in FIG. 11;

50 FIG. 14 is a combined transverse section and plan view taken generally along line 14—14 in FIG. 11;

FIG. 15 is a sectional plan view taken generally along line 15—15 in FIG. 11;

55 FIG. 16 is a vertical section of one of the elevating platform or platen assemblies of the machine illustrating the same in lowered position for receiving a container on the platen;

FIG. 17 is a partial view similar to FIG. 16 illustrating the position of certain parts of the assembly when the 60 assembly is in its fully elevated position when jars of less than maximum height are being capped;

FIG. 18 is a transverse section taken generally along line 18—18 in FIG. 16;

65 FIG. 19 is a transverse section taken generally along line 19—19 in FIG. 16;

FIG. 20 is a fragmentary side elevation as viewed along line 20—20 in FIG. 16;

70 FIG. 21 is a fragmentary, partly sectioned plan view of a portion of the machine as viewed along line 21—21 in FIG. 1;

FIG. 22 is a sectional view in elevation of a portion

of the machine illustrated in FIG. 21 taken generally along line 22—22 therein;

FIG. 23 is another partly sectioned elevation taken generally along line 23—23 in FIG. 21;

FIG. 24 is an enlarged partial vertical section of the evacuation and cap application chamber forming a part of the machine;

FIG. 25 is a vertical section taken generally along line 25—25 in FIG. 24;

FIG. 26 is a view similar to FIG. 24 illustrating operational use of certain of the components of the chamber;

FIG. 27 is a transverse section of the jar gripping arrangement of the chamber taken generally along line 27—27 in FIG. 26;

FIG. 28 is a partial view similar to those of FIGS. 24 and 26 illustrating additional operational aspects of the chamber;

FIGS. 29—31 are views similar to FIG. 28 illustrating operational aspects of the chamber;

FIG. 32 is a view similar to FIG. 26 illustrating cap application to a container;

FIG. 33 illustrates an enlarged detailed cross section of the container gripping arrangement;

FIG. 34 is a partial section of the chamber illustrating unused cap rejection therein;

FIG. 35 is a side elevation of the cap delivery device of the present invention;

FIG. 36 is a sectional plan view of the device taken generally along line 36—36 in FIG. 35;

FIG. 37 is a sectional plan view of the device taken generally along the line 37—37 in FIG. 35;

FIG. 38 is a fragmentary end elevation of the device as viewed from line 38—38 in FIG. 35;

FIG. 39 is a partial schematic view of the container feeding arrangement of the invention illustrating certain components thereof in plan view;

FIG. 40 is a view similar to FIG. 39 illustrating the elements in different operative positions; and

FIG. 41 is a diagrammatic layout of a typical cycle of operation of the machine of the invention illustrating certain cam track contours and their relative actions.

The vacuum capping machine as best shown in FIG. 1 includes a center upstanding column 10 suitably secured at the bottom thereof to a base member 11. The column 10 is provided with an axially extending passage 12 closed off at the bottom thereof by a plug 13 and terminating upwardly beyond the midpoint of the column. The upper end of the passage 12 has associated therewith a plurality of radially outwardly directed openings 14 extending through the column 10. The upper end of the column 10 is provided with a separate axially directed passage 15 which at the upper end thereof is in communication with a conduit 16 suitably attached to the column 10. The lower end of the passage 15 communicates with a plurality of radially directed openings 17 extending through the column 10. The lower end of the passage 12 is in communication with a conduit 18 which is suitably secured to the column 10 and extends radially outwardly therefrom through the base member 11. The passage 12 including the conduit 18 provides for the delivery of an inert gas, such as nitrogen, for use in the machine in a manner to be described. The passage 15 through its associated conduit 16 is connected to a suitable vacuum source (not shown) for a purpose to be described.

The base member 11 has as a part thereof a drive arrangement including a gear housing 20 in which a plurality of gears 21, 22, 23 (see FIG. 4), 24, 24D, and 25 are suitably mounted. The gear 21 is driven through a gear box 26 suitably mounted on the base member 11 from opposite sides of which extend a pair of drive shafts 27 (see FIG. 4) one of which may be connected to a motor (not shown) and the other of which may be used as a power take-off means for driving a conveyor or the like. The gear box 26 further includes an upwardly directed

driven gear 28 which is meshed with a large gear 30 fixedly secured to an annular flange member 31 formed integral with a vertical sleeve portion 32 of a container supporting assembly which is generally designated by the numeral 33.

The container supporting assembly 33 basically includes an annular radially projecting platform portion 34 integrally formed with the sleeve portion 32 and mounting therein through peripherally located, circumferentially spaced groove-like openings 35 a plurality of container supporting and lifting platform or platen assemblies generally designated by the numeral 36. The sleeve portion 32 of the container supporting assembly 33 is supported on sleeve bearings 37 at its upper and lower ends about the column 10 for rotation thereabout as driven by the gears 28 and 30. The top surface of the base member 11 has secured thereto an annular cam track 38 the top surface of which operatively engages a cam roller 40 forming a part of each platen assembly 36. The track 38 functions to control operation of the platen assemblies 36 during rotation thereof about the center column 10. In this regard each platen assembly 36 includes a container supporting and lifting platen 41 on which a container 42 is positioned, the left-hand platen 41 as viewed in FIG. 1 having been raised by the cam track 38 to place the container 42 supported thereon in a bell-shaped chamber 43 of a vacuum chamber and cap application assembly 44 positioned thereabove. The right-hand platen 41 as viewed in FIG. 1 is in its lowermost position as controlled by the associated portion of the cam track 38 and the container 42 supported thereon is free from the chamber 43 of the assembly 44 positioned thereabove.

Mounted above the container supporting assembly 33 is a container evacuation and capping assembly generally designated by the numeral 45. This assembly includes a housing 46 mounted on the center column 10 for rotation thereabout in synchronized relation with the container supporting assembly 33. The housing 46 defines a large annular vacuum chamber 47 with which the passage 15 of the column 10 is in communication through the openings 17. The chamber 47 has mounted therein a plurality of circumferentially spaced, radially directed stiffening ribs 48 which also act as baffle plates in cooperation with the relatively large size of the chamber to minimize the pulsation of air drawn through the chamber 47 during operation of the machine. Below the chamber 47, the housing 46 is formed with a second smaller annular chamber 50 having therein an apertured annular insert 51 and circumferentially spaced stiffening 45 rib baffles 52 (see FIG. 3). The insert 51 provides communication with the openings 14 of the passage 12 of the column 10 for a supply of inert gas during operation of the machine. The lower end of the housing 46 has depending therefrom a plurality of circumferentially spaced, fixed drive pins 53 the lower ends of which are clamped in locking collars 54 mounted in the radial plate 34 of the container supporting assembly 33. In this manner, the upper assembly 45 is rotatably driven by the lower assembly 33 to thus make use of a single power source in operating the machine.

The container evacuation and capping assembly 45 further includes a radially directed annular plate member 55 provided with a plurality of circumferentially spaced openings therein adjacent the outer periphery thereof in which the vacuum chamber and cap application assemblies 44 are removably mounted. Each of these assemblies generally includes the barrel-shaped container receiving chamber 43, a valve assembly 56, a cap delivery assembly 57, and an upwardly projecting cam actuated operating portion 58. The operating portion 58 is controlled by a cam roller 60. The valve assembly 56 is operated by a plurality of cam rollers 61. The cap delivery device 57 is operated by a pair of cam rollers 62. The valve assembly 56 is suitably connected to the

vacuumization chamber 47 by a pipe 63 and is suitably connected to the inert gas supply chamber 50 through a pipe 64. A suitable cap delivery chute is positioned relative to the machine as indicated by the broken lines identified by the numeral 65 (also see FIG. 5). Caps are delivered by this chute to each cap delivery device 57 when the same is withdrawn outwardly from its associated chamber 43 as shown in the right-hand portion of FIG. 1. The left-hand portion of FIG. 1 illustrates a cap delivery device 57 engaged with its associated chamber 43 during the evacuation and cap application operation of the machine.

The machine further includes a cam actuating assembly generally designated by the numeral 66. This assembly includes an internally threaded vertical adjustment sleeve 67 received about the upper end of the column 10 and supporting a vertically slidable non-rotatable, spline connected sleeve portion 68 on the column. Annular thrust bearings 70 are mounted at the lower end of the sleeve 67 in supporting engagement with portions of the sleeve 68. The upper end of the housing 46 of the container evacuation and cap application assembly 45 is at least partially supported on the sleeve 68 through a rotatable bearing structure 71. The top portion of the sleeve 67 is provided with a collar 72 to which a suitable lever or wrench bar 73 may be attached to raise or lower the sleeve 67.

The cam actuating assembly 66 further includes a radially directed annular plate 74 which has mounted thereon about the outer periphery thereof a cam track member 75 in which the cam rollers 60 of the vacuum chamber and cap application assemblies 44 are received. The cam track 75 opens outwardly of the machine thus permitting ready withdrawal of the cam rollers 60 therefrom. The assembly 66 further includes a depending sleeve-like cam track portion 76 which on the outer surface thereof is provided with a plurality of circumferentially variable cam tracks engaging the cam rollers 61 and 62 of the vacuum chamber and cap application assemblies 44.

The particular arrangement described regarding the positioning and type of cam tracks used in the machine is of special importance in connection with efficiency in machine operation and maintenance. The cam actuation assembly 66 is fixed against rotation on the center column 10 and the cam track portion 76 thereof extends downwardly between the chamber assemblies 44 and the center column to permit ready removal of any assembly 44 for maintenance or replacement purposes. In other words, the chamber assemblies 44 may be individually removed from the machine without disturbing any other operating mechanism or part of the machine and the arrangement is such that replacement of a chamber assembly 44 on the machine results in automatic alignment of the various cam actuated parts thereof with the cam track portions of the assembly 66. Furthermore, regardless of from what portion of the cycle a chamber assembly is removed, replacement of the same or a new assembly in the same portion results in immediate adjustment of the assembly to conform to the particular portion of the cycle.

The container evacuation and capping assembly 45 is vertically adjustable with the cam actuating assembly 66 along the center column 10. The assembly 45 is, in effect, rotatably supported on the sleeve 68 through the rotatable bearing means 71. Of course, this assembly is further supported by the container supporting assembly 33 through the drive pin arrangement including the pins 53 and locking collars 54. The interconnected assemblies 45 and 66 may be adjusted vertically relative to the container supporting assembly 33 by threaded movement of the sleeve member 67 of the assembly 66 along the upper threaded end of the column 10. All other column engaging parts will slide therealong upon loosening of the

drive pin arrangement. A change in vertical positioning of the upper assemblies will be necessary when the machine is used with containers of less than maximum height. During vertical adjustment of the interconnected assemblies 45 and 66, the interengaging operational parts thereof will maintain their cooperative positions. Thus no special adjustments are necessary other than a raising and lowering of the interconnected assemblies.

Referring to FIGS. 1-4, to one side of the machine and arranged tangentially relative thereto is an endless conveyor 77 carried on a suitable frame 78 and adapted to deliver containers to and from the vacuum capping machine. A container guide plate assembly 80 is suitably mounted on the conveyor 77 and projects over an adjacent portion of the plate 34 of the container supporting assembly 33. The guide plate assembly is provided with a container delivery slot portion 81 and a container removal slot portion 82. The conveyor 77 and guide plate assembly 80 constitute a portion of a container feed and take-off device which among its elements includes a uniquely designed and arranged container position control means 83 rotatably mounted on shaft 84 connected to the gears 24 and 24D. The control means is in the form of a pair of cooperating disc-like members as best shown in FIG. 1. The control means may be in the form of a starwheel of a type to be described and includes at least one pocket portion 85 in which a container is received from the conveyor 77 and delivered onto a platen 41 of the plate 34. Each pocket portion 85 is specially designed as will be described to provide for the introduction of a container onto the container supporting assembly 33 at a velocity equal to the rotational speed of the supporting assembly and further providing for positive holding of the container on a platen 41 until at least the top of the container is received in capping chamber 43.

A synchronizing container feed control means in the form of a rotating disc-like member 86 is mounted on a shaft 87 operated by the gear 25. This member is provided with at least one container receiving pocket portion 88 and operates to positively separate each container delivered thereto on the conveyor 77 for proper feeding thereof to the container position control means 83. The container feed and take-off device is completed with the provision of a container helper member 90 which projects into the slot portion 82 of the guide plate assembly 80. The helper member 90 rotates on a shaft 91 driven by the gear 23. This member is provided with at least one concave edge portion 92 designed to engage a container and move the same from a platen 41 of the container supporting assembly 33 onto the conveyor 77 following capping of the container.

With the basic elements of the machine having been generally described, FIG. 3 illustrates the operational portions of a complete cycle of operation involving 360° rotation. Capless containers 42 are delivered by the conveyor 77 into the slot portion 81 of the guide plate assembly. The synchronizing feeder member 86 provides for controlled delivery of the containers to the container position control means 83 which automatically places each container on a lowered platen 41 carried by the container supporting assembly 33. As the container moves counterclockwise in the machine as viewed in FIG. 3, the platen supporting the same is slowly raised by the cam track 38 and eventually the top of the container is at least partially received in a chamber 43 of an overhead evacuation and cap application assembly 44. The position control means 83 maintains engagement with the container until the overhead chamber receives at least a portion thereof thus preventing spilling or crushing of the container during high speed operation of the machine.

The cycle of the operation continues through the second quadrant during which a chamber 43, in which the container is enclosed, is evacuated and inert gas is used to sweep the same. Upon passing through the third

quadrant, the container still confined in a chamber 43 is supplied with a cap which is automatically twisted thereon in complete sealing engagement. Additional operations occur in the third quadrant of the cycle as indicated by the legends on FIG. 3 and these particular operations will be subsequently described. Upon entering the fourth quadrant, the vacuum established in the chamber 43 containing the capped container therein is released and the platen 41 supporting the container is lowered in time for the container to be received in the slot portion 82 of the guide assembly 80. The container is then ultimately engaged by the helper member 90 which provides for a positive movement of the container onto the conveyor 77 by means of which it is taken away from the machine. As indicated in FIG. 3, the empty platen as it passes through the guide plate assembly 80 after having a capped container removed therefrom and prior to receiving an uncapped container thereon may be subjected to automatic cleaning to remove any product that might accumulate thereon. Any suitable means may be utilized to provide a cleaning action in the cleaning zone such as an air jet.

FIG. 5 illustrates a portion of the cap delivery chute 65 the position of which relative to the machine is diagrammatically illustrated in FIG. 1. The chute 65 may be of any known type having an open end portion which cooperates with elements of the cap delivery device 57 in a manner which will be described. Among other things, the device 57 includes a cap receiving plug or boss 93 which is disc-shaped to be received within a known type of rotatable cap 94. The cap 94 consists essentially of a face panel having a depending annular skirt portion suitably provided with means for engaging interrupted locking lugs on the top outer surface of a container such as a glass jar 42. The cap 94 also carries a suitable gasket internally thereof in which is impressed the top edge of the open neck of a jar to provide for a hermetic seal. Cap application to the boss 93 may be positively controlled by a roller assembly 95 located at the open end of the cap delivery chute 65.

FIGS. 6-10 illustrate one of the container vacuum chamber and cap application devices 44 of the machine in connection with the basic operating means therefor. The device includes the bell-shaped chamber portion 43 which opens downwardly to receive therein a filled container for evacuation and capping thereof during operation of the machine. As previously described, the entire device 44 is removably mounted on the rotating plate 55 by means of suitable fasteners 96. The chamber 43 includes a cap delivery side opening 97 therein and a manifold-type portion 98 to which the valve assembly 56 is attached. The top central portion of the chamber 43 receives therethrough a reciprocating shaft member 100 which at the lower end thereof has mounted thereon a cap application and filter unit 101. Attached to the top of the chamber 43 is a housing member 102 which, as best illustrated in FIG. 10, is partially open along a side portion thereof. A pulley-type member 103 is received about the shaft 100 within the housing portion 102 and projects slightly therefrom through the side opening therein. The lower end of the pulley 103 is journaled in a rotatable bearing unit 104 carried by the housing portion 102 and at the top thereof is journaled in a similar bearing unit 105 which is carried by an upper housing portion 106 secured to the top of the housing portion 102. A portion of the shaft 100 extending through the pulley member 103 is provided with axially directed splines or ribs 107 which are received in cooperating grooves in the core of the pulley member 103 thus providing for vertical reciprocal operation of the shaft 100 through the pulley member 103 and its associated housing portions. Rotation of the pulley member 103 will result in rotation of the shaft 100 and the cap application and filter unit 101 attached thereto, the pulley member 103 being rotatable relative to the housing portions 102 and 106 which mount the same.

The top end of the shaft 100 extends upwardly through the housing portion 106 into a capping pressure adjustment assembly 108. This assembly includes a top plate 110 having an externally threaded depending sleeve portion 111 through which the top end of the shaft 100 is vertically slidably received. Fixed to the plate 110 is a cam roller mounting unit 112 to which the cam roller 60 is rotatably attached. The sleeve portion 111 receives thereabout a spring pressure adjusting member 113 which, as best shown in FIG. 8, is provided with a plurality of circumferentially spaced set screw notches on the outer periphery thereof with which a set screw 114 functions to lock the member 113 in a prescribed adjusted position axially along the sleeve portion 111. A spring 115 is received about the shaft 100 in end abutment with the adjusting member 113 and a shoulder portion of a slidable sleeve member 116 forming a part of the capping pressure adjustment assembly 108. The sleeve member 116 mounts a rotatable bearing unit 117 between the same and the shaft with the shaft race being fixed thereon between a threaded nut 118 and the upper ends of the ribs 107. The sleeve 116 is received in an outer sleeve 120 which is slidably mounted in the upper portion of the housing 106 and to the upper end of which is secured the cover plate 110.

The upper end of the housing 106 is in the form of a sleeve and is provided with a pair of oppositely positioned, axially extending guide slots 121 in which key members 122 slide. These members as shown in FIGS. 6 and 9 are suitably attached to the outer sleeve 120 of the capping pressure adjustment assembly 108. The upper end of the housing 106 is provided with an opening 123 aligned with an opening 124 in the outer sleeve 120 by means of which access can be gained to the adjusting member 113 to threadedly advance or retract the same on the sleeve portion 111. As shown in FIG. 8, another opening 125 is provided in the upper end of the housing 106 for access to the set screw 114 threadedly mounted in the outer sleeve 120.

In the operation of the various elements described above, it will be appreciated that the chamber 43 and attached housings 102 and 106 are fixedly mounted in the machine. FIG. 6 illustrates the retracted position of the cap application and filter unit 101 and shaft 100 in the assembly. During rotation of the assembly 44, the cam track 75 will vary and will result in downward movement of the shaft 100 including the capping pressure adjustment assembly 108 and the cap application and filter unit 101. The shaft 100 will slide downwardly through the pulley member 103 which is vertically fixed. The extent to which the spring 115 is compressed in its initial adjustment will determine the extent of capping pressure applied through the shaft 100. In other words, when a predetermined pressure is reached, further downward movement of the shaft 100 will terminate even though the cam roller assembly 112 continues to force the assembly 108 downwardly. Under such conditions the predetermined expansion force of the spring 115 is overcome causing the spring to compress further and the cover plate 110 and outer sleeve 120 will move downwardly relative to the shaft with the shaft remaining vertically fixed with the upper end thereof projecting out of the top of the cover plate 110. The spring 115 is further compressed to the extent where it will give the desired capping pressure.

The pulley member 103 as previously described is designed to impart rotation to the shaft 100 and attached cap application and filter unit 101 for rotation of a cap carried by the unit 101 in applying the same to a container. The outer surface of the pulley member 103 may be provided with a friction member of composition or rubber if desired for cooperation with a fixed shoe element 126 shown in phantom in FIG. 1 and as shown in FIG. 2. The shoe 126 is suitably carried by a supporting member 127 attached to the top plate 74 of the cam

actuating assembly 66. Thus the shoe 126 is fixed at a point of cap application in the rotational cycle of the machine. As each vacuum chamber and cap application assembly 44 passes the shoe 126, the same engages the pulley member 103 thereof and rotates the same through a prescribed arc which results in a rotation of the shaft 100 to the same extent. In this manner the cap is twisted onto the container.

FIGS. 11-15 illustrate in detail the cap application and filter unit 101. The bottom end of the shaft 100 is formed with a reduced end portion which has a series of circumferentially spaced, axially extending spline-like ribs 128 thereon. A collar member 130 is received thereabout and is provided with a plurality of grooves 131 in the lower portion thereof in which the ribs 128 are received thus providing for axial sliding of the collar 130 and other units attached thereto along the reduced end of the shaft 100 and further keying the collar and units attached thereto for rotation with the shaft 100 during cap application. The bottom end of shaft 100 is provided with a bore 132 in which one end of a coil spring 133 is seated. The opposite end of this spring is suitably fixed to an inner central surface portion of a magnet holder 134 which is suitably threaded on the bottom portion of the collar 130. A permanent magnet 135 is mounted in the bottom outer surface of the holder 134 and projects downwardly therefrom.

A rigid porous filter member 136 is fixedly mounted between the magnet holder 134 and the collar 130. The filter 136 is preferably formed from sintered metal beads or the like and is of inverted cup-like shape. The upper end surface of the filter 136 is provided with a flat-sided aperture for mounting in rotational driven relation between the members 130 and 134 and the lower edge thereof is provided with a circumferentially continuous, radially outwardly directed flange portion 137. The bottom edge of the filter 136 is held in engagement with a gasket 138 which is of generally L-shape in cross section. The gasket 138 is fixedly mounted in an inner circumferential groove 140 of a collar 141 which is received about the filter 136. The upper end of the collar 141 is provided with an inwardly directed flange portion which retains therein a spring member 142 in abutment with the upper surface of the flange 137 of the filter 136. As will be described in detail and as is partially shown in FIG. 12, the filter unit upon extended upward movement of the shaft 100 will compress the spring 142 to recess the magnet 135 further into the collar 141 and away from the gasket 138 to provide for the rejection of any cap which has not been accepted by a container. In this regard, the gasket 138 is shaped to conform to the outer edge configuration of a cap with the magnet 135 functioning to hold the cap in the collar 141 in engagement with the gasket 138. The spring 133 urges the unit 101 downwardly toward the end of the shaft 100 and separation of the unit from the shaft is prevented by a transverse locking pin 143 which extends through the shaft within the collar 130 for engagement with an inner surface portion of the top of the housing 130. The spring 133 adds a requisite degree of resiliency to the capping pressure during cap application use of the unit 101 for mating of cooperating thread portions of the cap and container.

FIGS. 16-20 deal with the structural and operational details of the container raising platen assemblies 36. Each assembly includes a tubular housing 144 which is suitably mounted in a groove 35 of the plate 34 of the machine. A platen supporting sleeve 145 extends upwardly through a bottom cover plate 147 of the housing 144 and projects outwardly above a top cover plate 148 thereof. The sleeve is suitably secured to the under surface of the platen 41. The upper and lower portions of the housing 144 suitably mount therein bearing sleeve members 150 which as best shown in FIG. 19 are split to define aligned slot portions in which a guide rib 146 fixedly mounted in the housing 144 is received. The sleeve 145 has an axially

extending groove 149 therein in which the guide rib 146 is received. Thus vertical reciprocal movement of the sleeve 145 through the housing 144 is provided for, while relative rotation is prevented.

5 The flanged lower end of the sleeve 145 has suitably connected thereto a cam roller assembly 151 which at the base thereof is provided with a cam roller 152 mounted on a pin 153 extending through parts of the housing. The housing includes a vertical guide slot 154 closed by a 10 cover plate 155. The cam roller 40 is mounted on a pin 156 which extends through a bifurcated plunger member 157 received in the housing 151. The upper end of the plunger member is in the form of a rod portion 158 which is received in the interior of the sleeve 145 and has seated thereagainst one end of a coil spring 160. The other 15 end of the coil spring is seated against the under surface of the platen 41. The pin mounting the cam roller 40 projects from the plunger member 157 into the guide slot 154 and the cam roller assembly may move upwardly in the housing 151 to compress the spring 160 as controlled by the elevation of the cam track 38. In this regard the portion of the housing 151 is slotted to receive any elevated cam track portion therein as shown in FIG. 17.

20 As previously described, the platen assembly 36 is raised after receiving a container on the platen 41 thereof and the raising is controlled by the cam track 38. The platen assembly moves upwardly until it abuts the chamber 43 of the overhead vacuum chamber and cap application assembly 44 in a manner to be described. The platen 41 25 actually closes off the bottom of the chamber 43 and during that portion of the cycle when the chamber is either evacuated or subjected to inert gas flushing, the corresponding portion of the cam track 38 is of sufficient height to bring about at least a partial compression of the spring 160. This aids in establishing a tight sealing engagement 30 between the platen and the bottom open end of the cooperating chamber.

35 Also as previously described, the entire container evacuation and capping assembly 45 and the cam actuating assembly 66 are vertically adjustable along the column 10 to accommodate containers of variable height. When containers of less than maximum height are to be capped, the assemblies 45 and 66 are lowered and it will be appreciated that the cooperating platen assemblies 36 need not necessarily rise to the same vertical height as required during the capping of containers of maximum height. Accordingly, the spring 160 will be compressed such as to the extent shown in FIG. 17 where full vertical travel of the platen 41 is not required and abutment 40 thereof in sealing engagement with an overhead chamber 43 is obtained at a lower height.

45 The outer cam roller 152 of each platen assembly 36 is arranged for operation on a separate cam track portion such as the portion 161 shown in broken lines in FIG. 1. This cam track portion is vertically adjustably mounted on the outer surface of the cam track 38 in the cap application portion of the cycle. As previously described, the caps used contain gaskets on the inner surface thereof and in order to obtain a tight hermetic seal, 50 it is desired that the top edge of the open end of the container be embedded in the gasket material. Thus at that portion of the cycle when the cap is actually twisted onto the container into tight sealed condition, the cam track portion 161 by engagement with the cam roller 152 backs up the platen assembly 36 to provide a reaction 55 force for the cap application force applied by the evacuation and filter unit 101 previously described. In this manner, separation of the platen 41 from sealing engagement with the bottom end of its associated chamber 43 is 60 prevented.

65 In connection with vertical adjustment of the upper assemblies 45 and 66, reference has been made to the use of a plurality of circumferentially spaced, vertically directed drive pins 53 which extend downwardly from fixed attachment to the lower end of the housing 46 of the as-

sembly 45 and which are clamped by locking assemblies 54 carried in the plate 34 of the container supporting assembly 33. FIGS. 21-23 illustrate the structural details of the interconnecting drive arrangement. It will be noted that the pins 53 each extend downwardly through an opening 162 in the plate 34 through which a locking member 54 projects. The locking member is in the form of a split clamping sleeve and includes a flanged portion 163 through which fasteners 164 extend to fixedly secure the locking member 54 to the plate 34. The locking member 54 is further provided with a pair of locking ears 165 which receive through aligned apertures therein, one of which is threaded, a threaded locking pin 166. The pin carries a limiting sleeve 167 thereon and secured thereto by a transverse pin 168. The outer end of the pin 166 is formed with a flat sided head portion 170 to which a suitable crank member may be attached to rotate the pin for tightening or loosening of the member 54. The arrangement described is important not only from the standpoint of providing means whereby the rotatable top assembly 45 is driven in synchronized relation with the bottom assembly 33 through a single drive means, but also from the standpoint that there is no "lost motion" involved. With this arrangement proper vertical coaction of the assemblies 33 and 45 is assured.

FIG. 24 illustrates the details of the valve assembly 56 which is attached to each chamber 43. The valve assembly includes a valve housing suitably detachably mounted on a chamber 43 in association with the manifold portion 98 previously described. The valve assembly housing includes three valve chambers 171, 172 and 173. The outer ends of the chambers define valve seats in the manifold area. Poppet valves 174, 175 and 176 close off the valve chambers and are operated on rods which carry at their opposite ends the cam rollers 61 previously described in FIG. 1. Any suitable spring arrangement (not shown) may be used in maintaining the valves in chamber sealing engagement with their respective seats. FIG. 25 illustrates the valve housing 56 as including a passage 177 extending from the chamber 171 into communication with the pipe 64 through which inert gas is supplied. The chamber 172 is in communication with an atmospheric vent 178 and the chamber 173 communicates through a passage 180 with the pipe 63 through which a vacuum is drawn.

The bottom open end of each chamber 43 is defined by a container gripping assembly 181 which is grooved along the bottom edge thereof and seats a platen engaging gasket 182. The assembly 181 is formed with a circumferentially continuous slot 183 in which a resilient container gripping member 184 is mounted. This member has a base portion of generally outwardly opening channel-like shape which is located outwardly of the slot 183. The gripping member is dimensioned to define spaces 185 between the same and the outer surfaces above and below the slot 183 for movement toward the surfaces into container gripping relation during operation of the machine in a manner to be described. The channel-shaped base portion of the gripping member 184 is received in a chamber 186 formed between the top and bottom chamber defining members of assembly 181 and which is in communication with atmospheric pressure through a plurality of openings 187 therein. The outer surface of the base portion is identified by the numeral 188 and is of substantial area for responsive action to atmospheric or other suitable pressure. The portion of the gripping member 184 which projects through the slot 183 is formed with a plurality of circumferentially spaced rib-like members 190. The projecting faces of these members are designed to engage the outer surface of a container.

Each vacuum chamber and cap application assembly 44 includes a cap delivery device 57 as previously described. FIGS. 35-38 best illustrate the structural features of the device. The chamber 43 has integrally formed therewith three transversely directed bores 191,

192 and 193. A rod 194 is received in the bore 191 for reciprocating movement therein. A rod 195 extends through the bore 192 for reciprocating movement therein. Similarly, a rod 196 extends through the bore 193 for reciprocating movement. The cap delivery device includes a sleeve-like housing 197 which at one end is sealed and at the other end is open for communication with the opening 97 in the chamber 43. The closed end of the housing 197 receives therethrough a reciprocating rod 198 which is connected to the rod 196 through a fixed link 200. The end of the rod 198 located within the housing 197 has suitably secured thereon the cap supporting boss 93 previously described.

The housing 197 is provided with a pair of oppositely directed ear portions having secured thereto the ends of the rods 194 and 195. The open end of the housing 197 is dimensioned for alignment with the opening 97 in the chamber 43 and is provided with a continuous gasket 201 which abuts the surface of the chamber 43 to completely seal off the opening 97 therein when the housing 197 is in engagement with the chamber as best shown in FIG. 36. The chamber 43 has staked thereto one end of a return spring 202, the other end of which is suitably staked to the housing 197. The chamber 43 also has staked thereto one end of a second return spring 203 which is suitably attached to the link 200.

Ends of the rods 195 and 196 are provided with the cam rollers 62 which engage the cam track portions of the sleeve 76 of the cam actuating assembly 66. The arrangement of the particular parts described permits controlled independent movement of the boss 93 into and out of the chamber 43 through the opening 97 and independent movement of the sleeve housing 197 into and out of engagement with the chamber 43 to seal off the opening 97. A number of the positions of these various elements throughout various portions of the cycle of operation of the machine are illustrated in FIG. 2.

FIG. 24 illustrates the positions of the various operative elements of a single evacuation and capping station at the time that a filled container 42 is placed on a supporting platen 41 below a chamber 43. This occurs during movement of the station through the loading zone as designated in FIG. 3. As shown in FIGS. 1, 2 and 24, by reason of cam actuation, the sleeve housing 197 of the cap delivery device is fully retracted on the rod 198 to expose the cap supporting boss 93 and a cap 94 is deposited thereon from the chute 65. The station then moves through the portion of the cycle during which the platform or platen 41 is raised lifting the container 42 into the chamber 43 as shown in FIG. 26. The platen 41 engages the chamber bottom sealing gasket 182 and the cap delivery sleeve housing 197 is cam actuated into sealing engagement with the chamber 43 about the cap delivery opening 97. In this portion of the cycle the cap supporting boss 93 is positioned within the sleeve housing 197 out of the chamber 43.

During the vacuumization and inert gas sweeping portions of the cycle as shown in FIG. 3, the cap application and filter unit 101 is lowered into engagement with the open top surface of the container 42. FIG. 26 illustrates the engagement of the top edge of the container by the gasket 138. The poppet valve 176 is opened by cam actuation and the chamber is evacuated. The container 42 is evacuated through the filter member 136. This filter member is preferably of deep cup design as illustrated to provide for a barometric leg effect in an effort to maintain at a minimum the time required to obtain a vacuum in the container. The deep cup design allows the particulate material to expand into a larger volume thereby making it easier for the air to escape from the product and also provides a greater filter area. The amount of vacuum drawn may be on the order of approximately 26½ inches of mercury vacuum. During evacuation of the chamber 43, atmospheric pressure acting on the outer

large face area 188 of the container gripping member 184 results in inward projection of the ribs 190 into engagement with the outer surface of the container. Thus with a differential pressure condition the ribs will engage the container and hold the same against rotation within the chamber 43. This engagement is best illustrated in FIGS. 27 and 33. The circumferential spacing of the ribs 190 provides for pressure equalization above and below the container gripping member 184 within the chamber 43 and the establishment of a vacuum condition below the container gripping member 184 aids in maintaining a tight seal between the platen 41 and the chamber gasket 182.

Following adequate evacuation of the chamber 43 and container 42, the vacuum control poppet valve 176 is closed as a result of cam actuation and the poppet valve 174 is opened as shown in FIG. 28. With the opening of this valve the supply of inert gas is placed in communication with the chamber 43 and this gas fills the chamber and passes in reverse flow through the filter member 136 into the container. This operational step is preferred in that the reverse flow through the filter member tends to keep the same clean and redeposit any particulate material collected thereon back into the container. An inert gas such as nitrogen may be bled back into the chamber 43 to raise the pressure therein to approximately 15 inches of mercury vacuum. Following this step, the inert gas valve 174 is closed and the vacuum control valve 176 may be reopened to reduce the pressure in the chamber 43 to the original 26½ inches of mercury vacuum. Further bleeding of some nitrogen to reduce the vacuum may be desirable to permit ready cap removal by a user. It has been found that this particular procedure results in the retention of only slightly over 1% oxygen in the container. Any number of vacuum and inert gas flushing cycles may be employed. The number of cycles used is controlled by the configuration of the cam tracks of the cam actuating assembly 66.

FIG. 29 illustrates the operation of the various elements during that portion of the cycle wherein the filter member 136 is raised out of operative association with the container and the cap is moved into the chamber. The cam track operating the rod 196 of the cap delivery device 57 provides for movement of the cap supporting boss 93 from within the sleeve housing 197 through the chamber opening 97 and into the chamber 43 between the cap application and filter unit 101 and the top of the container 42. During this operation the chamber 43 remains completely sealed and vacuum conditions prevail as the sleeve housing 197 of the cap delivery device completely seals off the opening 97 in the chamber 43.

FIG. 30 illustrates return downward movement of the cap application and filter unit 101 to an extent necessary to engage the cap 94 delivered into the chamber 43. The magnet 135 is of sufficient strength to lift the cap 94 from the boss 93 with the cap being held in engagement with the gasket 138. With retraction of the cap application and filter unit 101 carrying the cap 94, the rod 198 with the boss 93 is retracted from the chamber 43 through the opening 97 and into the sleeve housing 197 as shown in FIG. 31. Thus the chamber is cleared for cap application while the same and the container are still evacuated.

FIG. 32 illustrates cap application to the container 42. The evacuation and filter unit 101 is again lowered with the cap 94 in place thereon and the cap is seated on the top open end of the container 42. The portion of the cycle designated in FIG. 3 pertaining to the twisting of the cap onto the container occurs as a result of contact of the pulley member 103 (FIG. 6) with the shoe member 126 (FIG. 1) in the manner previously described. The shaft 160 rotates to the extent controlled by the effective length of the shoe member 126 and the cap 94 is twisted onto the container 42 in hermetic sealing relation. During twisting, the container 42 is held in fixed relation by the gripping member 184 previously described. FIG. 33

illustrates the effect of atmospheric pressure on the large outer face 188 of the gripping member in forcing the ribs 190 into the chamber 43 in tight engagement with the container 42. In comparing FIG. 33 with FIG. 24, it will be noted that the spaces 185 are filled by resilient contraction of the gripping member 184 in response to atmospheric pressure.

As mentioned above, proper hermetic sealing requires the embedding of the top edge of the container in the gasket material carried in the cap 94. Thus the downward pressure of the evacuation and cap application unit 101 must be rather substantial. In order to prevent the reaction force from separating the platen 41 from the bottom gasket 182 of the chamber 43, the outer cam roller 152 of the platen assembly 36 is placed in operation against the cam tracks segment 161 shown in FIGS. 1 and 17. This momentary contact between the cam roller 152 and the short cam track 161 provides a solid base for the platen assembly adequate to overcome any cap application reaction force.

Referring again to FIG. 32, following completion of the cap application portion of the cycle, the poppet valve 175 is opened by cam actuation as indicated in broken lines and the chamber 43 is vented to the atmosphere. In this manner the vacuum within the chamber is broken and the container gripping member 184 retracts to its original position to permit ready withdrawal of the container from the chamber. Furthermore, the sleeve housing 197 of the cap delivery device 57 is free to move away from the chamber 43 and back along the rod 198 to completely expose the boss 93 as in FIGS. 5 and 24 to permit delivery of another cap thereto to start the cycle again. The evacuation and filter unit 101 is moved upwardly in the chamber 43 and the platen 41 is lowered to withdraw the container from the chamber 43. The platen 41 readily separates from the chamber 43 by reason of the vacuum having been broken therein.

Retraction of the evacuation and filter unit 101 within the chamber 43 at this point of the cycle is carried out to the extent illustrated in FIG. 34. In the event that a cap 94 is not properly accepted by a container 42, or in the event that the container supply may be momentarily interrupted to an extent that no container is actually present in one of the capping stations during operation of the machine, means are provided whereby an unused cap may be rejected from the cap application and filter unit 101. As previously described, this unit includes the outer collar 141 which is spring mounted on the filter member 136. Upon final retraction of the unit 101 within the chamber 43, the camming action is controlled to draw the unit upwardly into the chamber 43 to an extent which exceeds the upward positioning of the unit during the other portions of the cycle. Thus the upper end of the collar 141 abuts a shoulder portion 204 formed in the inner top portion of the chamber 43. Continued upward movement of the filter member 136 results in compression of the spring 142 and a separation of the filter member from the gasket 138. As the unused cap is held against the gasket 138 and the magnet 135 moves with the filter 136, adequate separation between the magnet and the cap 94 occurs to a degree that the cap is no longer held by the magnet and the same drops downwardly out of the chamber 43 as illustrated in broken lines in FIG. 34. The unused cap will fall downwardly onto the lowered platen 41 and can be swept from the machine in the cleaning zone of the cycle designated in FIG. 3.

FIGS. 39 and 40 deal with the details of operation of the container feed and take-off device forming a part of the present invention. Referring preliminarily to FIGS. 2 and 3, it will be noted that the machine described above includes ten stations requiring the use of a container position control means 83 having two pocket portions 85 and a feed control means 86 having two pocket portions 88. FIGS. 39 and 40 illustrate control means incorporating the same principles of design but being adapted for use

with a machine having twenty stations thus requiring four pocket portions on each of the control means.

The container position control means 205 is mounted for rotation on the shaft 34 and is formed with four identical container pocket portions. The synchronizing feed control means 206 is mounted for rotation on shaft 37 and is formed with four container receiving pocket portions. Each of these control means are in the form of starwheels and project across the guide slot 31 of the guide plate assembly 80 previously described. Each pocket portion of the starwheel 205 is formed with a container pushing edge which is defined by continuous curvilinear surface portions including an innermost concave portion 207 which is of adequate radius to at least generally conform to the radius of a container 42, a convex portion 208 which functions to impart adequate velocity to a container delivered onto the rotating container supporting assembly 33 of the machine, and an outermost rearwardly tapering portion 210 which maintains contact with a container 42 for continued velocity and position control thereof until the container is adequately received in a capping chamber 43.

The starwheel 206 is of generally rectangular shape being provided with peripherally spaced concave pocket portions 211 of a radius conforming generally to that of a container 42. One end of each pocket terminates in a blunted projecting portion 212 joined with an outer flat surface portion which function to positively separate containers and seat one thereof in a pocket of the starwheel 205 in effective engagement with the concave inner portion 207 thereof. Thus as shown in FIG. 39, the container D has just been deposited in a pocket of the starwheel 205 and a blunt end 212 of the starwheel 206 is still in engagement with the container D to positively seat the same in engagement with the concave inner portion 207 of the pocket of the starwheel 205. The blunt end 212 further functions in separating containers 42 being delivered along the guide slot 31 for separate synchronized feeding thereof to the starwheel 205. This feature is particularly illustrated in FIGS. 39 and 40 with regard to the container C. The blunt end 212 of the starwheel 206 and its associated flat outer surface portion 213 functions in separating the container C from the container B and in holding back the container B and any other containers lined up behind the same until the next pocket 211 comes around to pick up the container B and positively separate the same from subsequent containers.

In considering the operation of the pushing edge of each pocket of the starwheel 205, it will be noted that container F in FIG. 39 has just been delivered onto the rotating container supporting assembly 33 of the machine and onto a platen 41 thereof. At this point the platen 41 begins to rise and continued rotation of the starwheel 205 results in the convex edge 208 pushing the container F as shown in FIG. 40 to a speed which is equal to the rotational speed of the platen 41 on which it is deposited. While adequate velocity is being imparted to the container F as shown in FIG. 40, positive positioning of the same on the associated platen 41 is maintained through cooperation between the starwheel 205 and the guide slot 31 of the guide plate assembly 80. The velocity imparting pushing action is continued as the outermost rearwardly tapering surface portion 210 of the guide slot engages the container as shown in connection with the container G in FIG. 39. Additionally, this continued engagement provides for continued position control of the container and at the position of the container G in FIG. 39, the platen 41 supporting the same has risen to a sufficient height for the top of the container to be at least partially received in the overhead capping chamber 43.

FIG. 41 diagrammatically illustrates the complete cycle of operation of the machine through 360°. The diagram includes the graphic representation of the camming cycle

for the filter-capping head unit 101 and for the elevating-platform platen assembly 36. This diagram additionally indicates the portions of the cycle in which the remaining cam track members operate to evacuate and flush with inert gas, inject the cap into the chamber 43 and retract the cap transfer shuttle or boss 93 from the chamber 43. It will be understood that other cycles may be readily set up with the machine described as controlled by variant cam track designs, additional cycles providing for multiple stages of vacuumization and inert gas flushing, etc. While a special form of jar gripping arrangement including the use of the special gripping means 184 has been described, other suitable arrangements may be used. With the gripping means 184, positive air pressure may be applied through suitable means to the rear face area 188 thereof in place of relying on atmospheric pressure.

Obviously certain modifications and variations of the invention as hereinbefore set forth may be made without departing from the spirit and scope thereof, and therefore only such limitations should be imposed as are indicated in the appended claims.

We claim:

1. A machine for automatically evacuating air from a filled container and capping the same, said machine comprising a center column, a container supporting assembly rotatably mounted on said column near the base thereof, a container evacuation and capping assembly rotatably mounted on said column above said container supporting assembly, drive means for said assemblies to rotate the same in synchronized relation, said container evacuation and capping assembly including container confining chambers spaced radially outwardly from said column, cam actuated evacuation means and cap delivery means forming a part of each chamber, and a cam actuating assembly mounted on said column above said container evacuation and capping assembly and fixed against rotation relative to said column, said cam actuating assembly having a portion thereof extending downwardly between said chambers and said column for actuation of said evacuation and cap delivery means.

2. The machine of claim 1 wherein each chamber including its evacuation means and cap delivery means is readily detachable from said evacuation and capping assembly and outwardly movable from said cam actuating assembly for maintenance or replacement thereof.

3. The machine of claim 1 wherein each container confining chamber includes a bell-type portion in which a container is received, a reciprocating cap application and filter unit received in the bell-type portion and including cam means engaged with a cam track portion of said cam actuating assembly located above said chambers, said cap application and filter unit being operated by said cam track portion to screen a container during the evacuation thereof and subsequently hold and apply a cap thereto received from said cap delivery means.

4. The machine of claim 1 wherein said container supporting assembly includes a plurality of container lifting platens which are cam actuated by cam means forming a part of said machine and which raise and lower each container into and out of sealed confinement in a chamber during a complete rotational cycle of said evacuation and capping assembly.

5. The machine of claim 1 wherein each container confining chamber includes a bell-type portion in which a container is received, said container supporting assembly including a plurality of container lifting platens which are cam actuated by cam means forming a part of said machine and which raise and lower each container into and out of sealed confinement in a chamber during a complete rotational cycle of said evacuation and capping assembly, a reciprocating cap application and filter unit received in the bell-type portion and including cam means engaged with a cam track portion of said cam actuating assembly located above said chambers, said

cap application and filter unit being operated by said cam track portion to screen a container during evacuation thereof and subsequently hold and apply a cap thereto received from said cap delivery means.

6. The machine of claim 1 wherein each container confining chamber includes a bell-type portion in which a container is received, said container supporting assembly including a plurality of container lifting platens which are cam actuated by cam means forming a part of said machine and which raise and lower each container into and out of sealed confinement in a chamber during a complete rotational cycle of said evacuation and capping assembly, a reciprocating cap application and filter unit received in the bell-type portion and including cam means engaged with a cam track portion of said cam actuating assembly located above said chambers, said cap application and filter unit being operated by said cam track portion to screen a container during evacuation thereof and subsequently hold and apply a cap thereto received from said cap delivery means, each chamber including its evacuation means and cap delivery means being readily detachable from said evacuation and capping assembly and outwardly removable from said cam actuating assembly for maintenance or replacement thereof.

7. The machine of claim 1 wherein the cam actuated evacuation means of each chamber includes a plural valving arrangement operated by said cam actuating assembly during rotation of said evacuation and capping assembly to evacuate a container and thereafter flush the same with an inert gas, said evacuation means further being connected with a pair of rotating housings surrounding said columns and rotatable with said evacuation and capping assembly, a first axial passage in said column and in communication with one of said housings, and a second separate axial passage in said column and in communication with the other of said housings, said first passage adapted for connection to a vacuum supply and said second passage adapted for connection to an inert gas supply.

8. A machine for automatically evacuating the head space of a filled container and capping the same, said machine comprising a center column, a container supporting assembly rotatably mounted on said column near the base thereof, a container evacuation and capping assembly rotatably mounted on said column above said container supporting assembly, drive means for said assemblies to rotate the same in synchronized relation, said container evacuation and capping assembly including container head space confining chambers spaced radially outwardly from said column, cam actuated head space evacuation means and cap delivery means forming a part of each chamber, and a cam actuating assembly mounted on said column above said container evacuation and capping assembly and fixed against rotation relative to said column, said cam actuating assembly having a portion thereof extending downwardly between said chambers and said column for actuation of said evacuation and cap delivery means, said drive means comprising power transmitting means connected with said container supporting assembly to rotate the same, and vertically adjustable rotation transmitting means interconnecting said container supporting assembly with said container evacuation and capping assembly, said evacuation and capping assembly and said cam actuating assembly each being vertically movable along said column to adjust said machine to containers of varying height.

9. The machine of claim 8 wherein said vertically adjustable rotation transmitting means comprises a plurality of circumferentially spaced drive pins extending vertically from one of said evacuation and capping or container supporting assemblies and fixed to the other of said assemblies by clamping means forming a part thereof.

10. A machine for automatically evacuating a filled container and capping the same, said machine compris-

ing a center column, a container supporting assembly rotatably mounted on said column near the base thereof, a container evacuation and capping assembly rotatably mounted on said column above said container supporting assembly, drive means for said assemblies to rotate the same in synchronized relation, said container evacuation and capping assembly including container confining chambers spaced radially outwardly from said column, cam actuated evacuation means and cap delivery means forming a part of each chamber, and a cam actuating assembly mounted on said column above said container evacuation and capping assembly and fixed against rotation relative to said column, said cam actuating assembly having a portion thereof extending downwardly between said chambers and said column for actuation of said evacuation and cap delivery means, said drive means comprising power transmitting means connected with said container supporting assembly to rotate the same, and vertically adjustable rotation transmitting means interconnecting said container supporting assembly with said container evacuation and capping assembly and said cam actuating assembly each being vertically movable along said column to adjust said machine to containers of varying height, said evacuation and capping assembly being at least partially supported on said cam actuating means by bearing means providing for rotation of said evacuation and capping assembly relative to said cam actuating assembly and said column.

11. The machine of claim 10 wherein said vertically adjustable rotation transmitting means comprises a plurality of circumferentially spaced drive pins extending vertically from one of said evacuation and capping or container supporting assemblies and fixed to the other of said assemblies by clamping means forming a part thereof.

12. In a container sealing machine wherein synchronized container supporting and cap application assemblies continuously operate to cap product filled containers, the provision of a container evacuation and cap application device forming a part of the cap application assembly, said device comprising a bell-shaped portion adapted to receive therein a container supported by the container supporting assembly, a gasket on the open edge of said bell-shaped portion for sealing engagement with a surface of the container supporting assembly to completely enclose a container in said bell-shaped portion, vacuum supply and control means forming a part of said device and in communication with the interior of said bell-shaped portion, a cap application and filter unit in said bell-shaped portion in the top thereof and provided with operating means extending from said bell-shaped portion to reciprocate said unit therewithin, a cap receiving opening in said bell-shaped portion, and cap delivery means forming a part of said device and including means for sealing communication with said opening in said bell-shaped portion to deliver a cap thereinto for use by said cap application and filter unit.

13. The device of claim 12 wherein said operating means for said cap application and filter unit comprises an upwardly directed shaft which at the top thereof has operatively connected thereto a cam unit adapted for controlled operation by cam actuating means of said machine, a shaft housing fixed to said bell-shaped portion with said shaft being mounted therein for reciprocation as brought about by said cam unit and for controlled rotation, and shaft rotation imparting means on said shaft and projecting from said shaft housing for engagement with shaft operating means forming a part of said machine.

14. The device of claim 12 wherein said vacuum supply and control means comprises a valve housing connected to said bell-shaped portion and in communication with the interior thereof through a passage in said bell-shaped portion, at least one cam actuated valve means in

said housing to control evacuation of said bell-shaped portion, and means communicating with said valve means for connection with a vacuum source of said machine.

15. The device of claim 12 wherein said cap delivery means comprises a sleeve-like housing closed at one end and provided with a gasket at the remaining open end thereof for sealing engagement with said bell-shaped portion about the opening therein through which a cap is delivered, cap supporting boss means carried on an end of a rod-like means extending longitudinally through said sleeve-like housing, first cam actuated operating means connected to said sleeve-like housing to move the same toward and away from said bell-shaped portion, and second cam actuated operating means connected with said rod-like means to move the same toward and away from said bell-shaped portion, said boss means being adapted to be positioned free of said sleeve-like housing to receive a cap thereon, said boss means being further adapted to be received in said sleeve-like housing outwardly of said bell-shaped portion when said housing is in sealing position about said opening and to be moved into said bell-shaped portion to deliver a cap to said cap application and filter unit.

16. The device of claim 12 wherein said bell-shaped portion includes a circumferential inwardly facing container gripping means, said gripping means being formed from resilient material and including an outer face portion which is exposed on the outer surface of said bell-shaped portion to atmospheric pressure, said gripping means being forced inwardly into rotation preventing engagement with a container when said bell-shaped portion is evacuated.

17. The device of claim 12 wherein said bell-shaped portion is provided with a circumferential slot portion in which an inwardly facing container gripping means is received, said gripping means having a base portion of generally outwardly opening channel-shape of a width preventing complete movement of said gripping means through said slot portion, the inner face of said gripping means being formed with a member projecting through said slot portion into said bell-shaped portion for engagement with a container, the outer exposed surface of said gripping means being of sufficient area to force said rib-like member into container rotation preventing engagement in response to atmospheric pressure when said bell-shaped portion is evacuated.

18. The device of claim 12 wherein said bell-shaped portion is provided with a circumferential slot portion in which an inwardly facing gripping means is received, said gripping means having a base portion of generally outwardly opening channel-like shape of a width preventing complete movement of said gripping means through said slot portion, the inner face of said gripping means being formed with a plurality of circumferentially spaced rib-like members projecting through said slot portion into said bell-shaped portion for engagement with a container, the outer exposed surface of said gripping means being of sufficient area to force said rib-like members into container rotation preventing engagement in response to atmospheric pressure when said bell-shaped portion is evacuated, the spacing of said rib-like members providing for pressure equalization above and below said gripping means in said bell-shaped portion.

19. In a container sealing machine wherein synchronized container supporting and cap application assemblies continuously operate to cap product filled containers, the provision of a container evacuation and cap application device forming a part of the cap application assembly, said device comprising a bell-shaped portion adapted to receive therein a container supported by the container supporting assembly, a gasket on the open edge of said bell-shaped portion for sealing engagement with a surface of the container supporting assembly to completely enclose a container in said bell-shaped portion, vacuum supply and control means forming a part of said device and

in communication with the interior of said bell-shaped portion, a cap application and filter unit in said bell-shaped portion in the top thereof and provided with operating means extending from said bell-shaped portion to reciprocate said unit therewithin, and cap delivery means forming a part of said device and adapted for sealing communication with an opening in said bell-shaped portion to deliver a cap thereinto for use by said cap application and filter unit, said cap application and filter unit comprising a centrally located magnet means surrounded by a filter assembly, said filter assembly including an inverted cup-shaped filter receiving thereabout a gasket retention collar spring mounted on said filter, a gasket carried by said collar and in spring held engagement with the bottom edge of said filter, said gasket being shaped to receive a cap therein as held by said magnet means and further adapted for sealing engagement with an open end portion of a container during evacuation thereof, and abutment means in said bell-shaped portion for engagement with said collar to move said gasket away from said magnet means for cap separation from said filter assembly.

20. A cap delivery device for use in a container sealing machine in which the cap receiving end of a container is received in a cap application chamber including cap applying means therein, said device comprising a sleeve-like housing closed at one end and provided with a gasket at the remaining open end thereof for sealing engagement with said chamber about a cap receiving opening therein through which a cap is delivered, cap supporting boss means carried on an end of a rod-like means extending longitudinally through said sleeve-like housing, first cam actuated operating means connected to said sleeve-like housing to move the same toward and away from said chamber, and second cam actuated operating means connected with said rod-like means to move the same toward and away from said chamber, said boss means being adapted to be positioned free of said sleeve-like housing to receive a cap thereon, said boss means being further adapted to be received in said sleeve-like housing outwardly of said chamber when said housing is in sealing position about said opening and to be moved into said chamber to deliver a cap to said cap applying means.

21. A container gripping arrangement for use in a container sealing machine in which a container is received in a confining bell-shaped portion of a rotatable cap application and container evacuation device, said container gripping arrangement comprising a circumferential slot portion in said bell-shaped portion in which an inwardly facing container gripping means is received, said gripping means having a base portion of generally outwardly opening channel-like shape of a width preventing complete movement of said gripping means through said slot portion, the inner face of said gripping means being formed with a rib-like member projecting through said slot portion into said bell-shaped portion for engagement with a container, the outer exposed surface of said gripping means being of sufficient area to force said rib-like member into container rotation preventing engagement in response to atmospheric pressure when said bell-shaped portion is evacuated.

22. A container gripping arrangement for use in a container sealing machine in which a container is received in a confining bell-shaped portion of a rotatable cap application and container evacuation device, said container gripping arrangement comprising a circumferential slot portion in said bell-shaped portion in which an inwardly facing container gripping means is received, said gripping means having a base portion of generally outwardly opening channel-like shape of a width preventing complete movement of said gripping means through said slot portion, the inner face of said gripping means being formed with a plurality of circumferentially spaced rib-like members projecting through said slot portion into said bell-shaped portion for engagement with a container, the out-

er exposed surface of said gripping means being of sufficient area to force said rib-like members into container rotation preventing engagement in response to atmospheric pressure when said bell-shaped portion is evacuated, the spacing of said rib-like members providing for pressure equalization above and below said gripping means in said bell-shaped portion.

23. A container feed and take-off device for use with a rotary container sealing machine which includes a rotating container supporting assembly adapted for cooperation with container receiving capping chambers forming a part of a container capping assembly which is synchronized for rotation with said container supporting assembly and for receiving containers on said supporting assembly in said capping chambers during said synchronized rotation, said container feed and take-off device comprising a container guide plate provided with a container guide slot arranged to direct a container onto said container supporting assembly over an edge thereof, a container conveyor below said guide plate to deliver and take away containers, a rotatable container position control means projecting across said guide slot, said control means including at least one pocket portion in which a container is received from said conveyor, said pocket portion having a container pushing edge of cam-like shape which moves a container onto said supporting assembly at a velocity equal to the rotational speed of said supporting assembly and holds the container in position until at least the top of the container is received in a capping chamber, and drive means for said control means.

24. The device of claim 23 wherein said container pushing edge is formed with continuous curvilinear surface portions including an innermost concave portion of adequate radius to at least generally conform to the radius of a container, an intermediate convex portion which functions to impart adequate velocity to a container, and an outermost rearwardly tapering portion which maintains contact with a container for position control thereof until adequately received in a capping chamber.

25. A container feed and take-off device for use with a rotary container sealing machine which includes a rotating container supporting assembly adapted for cooperation with container receiving capping chambers forming a part of a container capping assembly which is synchronized for rotation with said container supporting assembly and for receiving containers on said supporting assembly in said capping chambers during said synchronized rotation, said container feed and take-off device comprising a container guide plate provided with a container guide slot arranged to direct a container onto said container supporting assembly over an edge thereof, a container conveyor below said guide plate to deliver and take away containers, a rotatable container position control means projecting across said guide slot, said control means including at least one pocket portion in which a container is received from said conveyor, said pocket portion having a container pushing edge of cam-like shape which moves a container onto said supporting assembly at a velocity equal to the rotational speed of said supporting assembly and holds the container in position until at least the top of the container is received in a capping chamber, a rotatable container synchronizing feed control means projecting across said guide slot, said feed control means including at least one pocket portion in which a container is received while on said conveyor and guided into the pocket portion of said position control means, and drive means for said control means.

26. The device of claim 25 wherein said container pushing edge is formed from continuous curvilinear surface portions including an innermost concave portion of adequate radius to at least generally conform to the radius of a container, an intermediate convex portion functioning to impart adequate velocity to a container, and an outermost rearwardly tapering portion which maintains

contact with a container for position control thereof until adequately received in a capping chamber.

27. A container feed and take-off device for use with a rotary container sealing machine which includes a rotating container supporting assembly having a plurality of container lifting platens vertically aligned with container receiving capping chambers forming a part of a container capping assembly which is synchronized for rotation with said container supporting assembly, said container feed and take-off device comprising a container guide plate provided with a first container guide slot arranged to direct a container onto a platen of said container supporting assembly over an edge thereof and a second container guide slot arranged to remove a container from a platen of said container supporting assembly, a container conveyor below said guide plate and extending tangentially to said container supporting means to deliver and take away containers, a rotatable container position control means projecting across said first guide slot, said control means including at least one pocket portion in which a container is received from said conveyor, said pocket portion having a container pushing edge of cam-like shape which moves a container onto a platen at a velocity equal to the rotational speed of said supporting assembly and holds the container in position until at least the top of the container is received in a capping chamber, and drive means for said control means.

28. The device of claim 27 wherein said container pushing edge is formed from continuous curvilinear surface portions including an innermost concave portion of adequate radius to at least generally conform to the radius of a container, an intermediate convex portion which functions to impart adequate velocity to a container, and an outermost rearwardly tapering portion which maintains contact with a container for position control thereof until adequately received in a capping chamber.

29. A container feed and take-off device for use with a rotary container sealing machine which includes a rotating container supporting assembly having a plurality of container lifting platens vertically aligned with container receiving capping chambers forming a part of a container capping assembly which is synchronized for rotation with said container supporting assembly, said container feed and take-off device comprising a container guide plate provided with a first container slot arranged to direct a container onto a platen of said container supporting assembly over an edge thereof and a second container guide slot arranged to remove a container from a platen of said container supporting assembly, a container conveyor below said guide plate and extending tangentially to said container supporting means to deliver and take away containers, a rotatable container position control means projecting across said first guide slot, said control means including at least one pocket portion in which a container is received from said conveyor, said pocket portion having a container pushing edge of cam-like shape which moves a container onto a platen at a velocity equal to the rotational speed of said supporting assembly and holds the container in position until at least the top of the container is received in a capping chamber, a rotatable container synchronizing feed control means projecting across said first guide slot, said feed control means including at least one pocket portion in which a container is received while on said conveyor and guided into the pocket portion of said position control means, and drive means for said control means.

30. The device of claim 29 wherein said container pushing edge is formed from continuous curvilinear surface portions including an innermost concave portion of adequate radius to at least generally conform to the radius of a container, an intermediate convex portion which functions to impart adequate velocity to a container, and an outermost rearwardly tapering portion which maintains

tains contact with a container for position control thereof until adequately received in a capping chamber.
